SPARK PLUG

Delbert E. Replogle, Ridgewood, N. J., assignor to
 Global Spark Plug Co., Paterson, N. J., a corporation of New Jersey

Application January 25, 1944, Serial No. 519,670

1 Claim. (Cl. 123—169)

1

This invention relates to spark plugs and particularly to high duty plugs, such as those for airplane engines.

The object of the invention is to provide a spark plug which will be strong and durable in service and permanently secure against short-circuiting and leakage of pressure.

A further object of the invention is to provide a method for the manufacture of such a spark plug insuring a firm bond between the parts.

In the accompanying drawings

Fig. 1 is a sectional view illustrating the construction of the spark plug and a step in the method of formation;

Fig. 2 is a similar view illustrating a subsequent step in the process of formation of this spark plug;

Figs. 3 and 4 are sectional views of a modified method of manufacture of a spark plug; and

Fig. 5 is a vertical sectional view of a special formation of the central part of the shell of the spark plug.

The spark plug of this invention comprises an outer shell 10 preferably of cold rolled steel, an insulator 11 at the lower portion of the shell, a molded insulation 12 filling the shell above the insulator 11, and a central electrode 14 preferably of molybdenum with an end or sparking point 15 of nickel or similar resistant metal.

The shell 10 has a tapered seat 16 for the insulator 11, a bushing 17 intervening between the insulator and the seat and being composed of copper or other soft metal providing an intimate sealing contact with the cooperating surfaces of the seat and insulator.

The insulation 12 is molded in place under heat and pressure in a manner giving a thorough leakproof seal while at the same time rigidly fixing all of the parts in place and insulating the rod or electrode 14 from the shell 10.

On the outside the shell 10 is provided with flange 18, nut portion 19 and threads 20 for the fastening of the spark plug in place in the engine.

The sparking end of the plug is provided with a recess 22 around the lower end 23 of the insulator 11 and a plurality of sparking points 24 are arranged around the end 15 of the central sparking electrode.

The top of the shell 10 is provided with an overhanging flange ring 30 forming a ledge around the recess 31 for the reception of the terminal connection, the inner end of which reaches and contacts with the head 32 at the top of the central electrode 14 at the bottom of

2

the recess 31. Screw threads 33 are cut around the outer end of the shell above the shoulder 34 to cooperate with the outer attaching sleeve of the standard terminal fitting in recess 31 and held therein by the screwing of the sleeve on to the threads 33.

As shown in Fig. 5 the head 320 on the electrode 140 may be specially shaped with a neck portion 35 between the ends 36, 37, the upper surface of the latter forming the bottom of the recess 310. The shell 100 may have its central portion 38 bulged outward in globular formation as shown to give additional thickness of insulation between the head and the shell and to aid in anchoring the molded insulation 120 securely in place.

In the formation of the spark plug the shell 10 is assembled with the liner or bushing 17 in place on the seat 16 and insulator 11 pressed into place. The rod 14 is then inserted with its lower end part way in the bore of the insulator (Figs. 1 and 3). The insulation 12 for molding is then supplied, preferably in powdered or granular form, substantially filling the shell 10 above the insulator 11, and a plunger 40 having a sliding fit in the flange ring 30 is forced downward into the shell to compress the insulation, the whole plug with the insulation being heated to a high temperature to render the insulation 12

30 plastic and moldable. As the plunger 40 descends, the pressure increases and the rod 14 moves downward with the plunger, the now plastic insulation flowing into all cracks and crevices of the shell and insulator parts and upward around the plunger 40 and under the flange ring 30 as indicated in Fig. 2. During this plunger action the lower end 15 of the rod 14 protrudes outward below the lower end of the spark plug an amount dependent upon the 40 length of movement of the plunger 40, and at the end of the plunger movement the molded insulation 12 has completely and tightly filled the entire space within the shell and has formed a permanent leakage-proof seal. The plunger

45 40 is then removed leaving the recess 31 with the contact head 32 at the bottom and the lower end 15 of the central electrode 14 is cut off about even with the sparking points 24 as shown for instance in Fig. 5.

50 The cooling of the molded insulation 12 hardens the insulation into solid glassy formation, all of the parts being tightly bound together. Preferably, the outer shell 10 is of material, such as cold, rolled steel, having a relatively high coefficient of shrinkage on cooling in comparison to

the material molybdenum, for instance, of the central rod 14, the shrinkage of the molded mass 12 being intermediate between these so that the sleeve of molded material 12 tightly grips the rod 14 and in turn is tightly gripped by the shrinking of the shell 10.

As illustrated in Figs. 3 and 4, the molded plunger 50 may be of hollow formation with a bore 51 sliding over the rod 82 forming the central electrode and the periphery of the plunger 50 having a sliding fit within the flange ring 30. The further depression of the plunger 50, for instance to the extent shown in Fig. 4, will cause the heated insulating material 12 to flow into all parts of the interior of the shell, and at the same time the electrode 82 will move downward with said material, in this case being received in the template 55, limiting its downward movement and positioning it relative to the sparking points 24. The plunger 50 is then removed and the recess 56 is formed similar to the recess 31 to receive the conventional terminal connection.

The molded insulation 12 is preferably of the glass bonded mica type as set forth for instance in U. S. Patent 1,795,200 and Re. Patent 15,727 to Crossley or U. S. Patent 2,032,239 to Wedlock, as this will give a firm bonding and sealing effect while at the same time providing a superior type of insulation.

The completed spark plug is strong and durable, effectively insulating the central electrode 14 and also absolutely tight against the leakage of pressure through the plug so as to be permanently leakproof.

I claim:

A shielded spark plug comprising a tubular metal shell having one end portion provided with a seat for an insulator and the other end portion

of cylindrical form with an intermediate central portion bulged outward to larger diameter in globular formation, a tubular insulator on said seat, an electrode passing through said insulator and connected at its inner end to a head member extending into said globular formation and having an intermediate narrow neck portion, and a molded insulation filling said globular formation and said shell behind said insulator and around said neck portion of said head to retain said insulator against its seat and lock said head in place in said globular formation and retain the parts against relative axial movement in either direction.
